UNITED STATES PATENT OFFICE.

WILLIAM A. LORENZ, OF HARTFORD, CONNECTICUT.

CONDIMENT-BOTTLE.

1,268,740.

Specification of Letters Patent.

Patented June 4, 1918.

Application filed February 17, 1917. Serial No. 149,347.

To all whom it may concern:

Be it known that I, WILLIAM A. LORENZ, a citizen of the United States, residing at Hartford, in the county of Hartford and State of Connecticut, have invented a new and useful Improvement in Condiment-Bottles, of which the following is a specification.

This invention relates to a bottle or jar which is particularly suitable for containing mustard, horse radish and other relishes, sauces and the like seasoning and appetizers for foods.

The object of the invention is to provide a bottle that is simple to manufacture, easy to seal so that the contained substance will keep in prime condition and will not leak during handling and transportation, readily unsealed by the consumer, and when sealed is in a neat and attractive condition for service on a table.

The object is attained by providing the bottle with an inner cover that may be used to temporarily close the mouth until the contents of the bottle are consumed, and with an outer cap which is held in place by atmospheric pressure and that seals the mouth and at the same time holds the cover in place while the bottle is being handled and transported.

In the accompanying drawings which illustrate the invention Figure 1 shows a plan of the closed bottle. Fig. 2 shows a plan of the cover. Fig. 3 is an elevation with the upper end of the bottle, the cover and the cap cut in section, the relation of the parts being that just before the bottle is sealed. Fig. 4 is a similar view with the parts in the positions occupied when the bottle is sealed. Fig. 5 is a section showing a modified arrangement for holding the cover closed when the bottle is sealed.

The bottle 1 may be made of glass, porcelain or other earthen ware, preferably the first, with a wide mouth. On the inside of the neck near the mouth the bottle has a flange 2 which provides a seat for the cover, and on the outside near the mouth the bottle is provided with a shoulder 3 which forms a seat for the seal.

The cover 4, which loosely fits into the mouth of the bottle, may be made of glass, porcelain or other material, and it is preferably recessed so that it has an annular exterior wall 5 and a central hub 6. This insures a light, strong cover provided with a

handle by which it may be conveniently lifted from or returned to the mouth of the bottle. An opening 7 is desirably made through the cover at one edge for the passage of the handle of a spoon or other implement that may be used to remove the contents of the bottle.

The cap 8 is preferably made of metal with a flaring rim 9. The top of the cap may be dished or may be formed with annular corrugations 10 in order to render it somewhat flexible.

A rubber gasket 11 is placed on the shoulder on the exterior of the bottle neck to provide a seat for the rim of the cap, and a rubber or paper gasket 12 may be placed on the cover seating flange in the interior of the mouth of the bottle. A waterproof paper disk 13 forming a temporary closure may be placed on the seat gasket inside of the cover, and a spring 14 may be arranged about the handle hub on the outside of the cover.

In utilizing this bottle after it has been filled with the food product the paper disk is placed on the gasket on the seat flange in the interior and the cover placed in the mouth on the gasket. Then the cap is put over the mouth of the bottle with its flaring rim resting lightly on the gasket on the shoulder on the exterior. Air is then exhausted from the interior of the bottle in the usual way, after which pressure is applied to the cap. When the cap is seated and again subjected to the outer atmosphere the normal pressure holds the cap tightly over the mouth of the bottle and forces the center of the cap in against the hub or the spring about the hub so as to press the cover in against the disk on the interior gasket. The cap and outer gasket tightly seal the bottle and the cap at the same time through the cover causes the disk and inner gasket to close the inside so that the contents of the bottle cannot leak out around the cover or smear the cover. If the spring is employed it would not be necessary to have the cap flexible, although it is desirable to have it so.

To gain access to this bottle it is only necessary to break the atmospheric seal on the outside and remove the cap which can be thrown away. Then when the cover is lifted out the paper disk and inner gasket can be removed and discarded. The bottle can then be used in the ordinary way, the

cover being utilized as a protecting closure as long as there is any thing in the bottle, and a spoon or other implement may remain in the bottle with its handle extending 5 through the notch in the cover.

The invention claimed is:

A hermetically sealable container comprising a jar having a shoulder in the interior and a shoulder on the exterior, a 10 gasket on the interior shoulder, a gasket on the exterior shoulder, a cover loosely fitted into the mouth of the jar and resting on

said inner gasket, and a cap with a corrugated top and a flexible rim fitted to the exterior gasket, whereby when said cap is 15 subjected to greater atmospheric pressure on the outside than on the inside its rim seats tightly on the exterior gasket and hermetically seals the jar on the exterior and its corrugated top collapses against the cover 20 and holds said cover tightly down on the interior gasket and hermetically seals the jar on the interior.

WILLIAM A. LORENZ.
